SUBTERRANEAN TRANSFORMER VAULT

Morris Greitzer, Los Angeles, and Simon Greitzer,
Inglewood, Calif., assignors to California Maple,
Los Angeles, Calif., a corporation of California

Filed Nov. 14, 1966, Ser. No. 4,633

Term of patent 14 years

(Cl. D13—1)

FIG. 1.

FIG. 2.

3

3

FIG. 3.

FIG. 1 is a perspective view of a subterranean transformer vault showing our new design;

FIG. 2 is an enlarged fragmentary cross-section taken on line 2—2 of FIG. 1; and

FIG. 3 is an enlarged cross-section taken on line 3—3 of FIG. 1.

We claim:

The ornamental design for a subterranean transformer vault, as shown and described.
